(57) **CLAIM**

The ornamental design for a finger tip stylus, as shown and described.

DESCRIPTION

FIG. 1 is a perspective View of the finger tip stylus according to a first embodiment of the present invention.

FIG. 2 is a top view of the finger tip stylus of FIG. 1.

FIG. 3 is a bottom view of the finger tip stylus of FIG. 1.

FIG. 4 is a rear view of the finger tip stylus of FIG. 1.

FIG. 5 is a front view of the finger tip stylus of FIG. 1.

FIG. 6 is a left side view of the finger tip stylus of FIG. 1.

FIG. 7 is a right side of the finger tip stylus of FIG. 1.

FIG. 8 is a perspective view of the finger tip stylus according to a second embodiment of the present invention.

FIG. 9 is a top view of the finger tip stylus of FIG. 8.

FIG. 10 is a bottom view of the finger tip stylus of FIG. 8.

FIG. 11 is a rear view of the finger tip stylus of FIG. 8.

FIG. 12 is a front view of the finger tip stylus of FIG. 8.

FIG. 13 is a left side view of the finger tip stylus of FIG. 8.

FIG. 14 is a right side of the finger tip stylus of FIG. 8.

FIG. 15 is a perspective view of the finger tip stylus according to a third embodiment of the present invention.

FIG. 16 is a top view of the finger tip stylus of FIG. 15.

FIG. 17 is a bottom view of the finger tip stylus of FIG. 15.

FIG. 18 is a rear view of the finger tip stylus of FIG. 15.

FIG. 19 is a front view of the finger tip stylus of FIG. 15.

FIG. 20 is a left side view of the finger tip stylus of FIG. 15; and,

FIG. 21 is a right side of the finger tip stylus of FIG. 15.
